Patented Dec. 26, 1916.

UNITED STATES PATENT OFFICE.

KNUT F. M. LINDBLAD, OF EVERETT, MASSACHUSETTS.

ADJUSTABLE SUPPORT FOR ELECTRIC LAMPS.

1,210,087.

Specification of Letters Patent. Patented Dec. 26, 1916.

Application filed February 26, 1916. Serial No. 80,721.

To all whom it may concern:

Be it known that I, KNUT F. M. LINDBLAD, a citizen of the United States, residing at Everett, in the county of Middlesex and State of Massachusetts, have invented new and useful Improvements in Adjustable Supports for Electric Lamps, of which the following is a specification.

This invention relates to an adjustable pendant for electric light lamps.

The object of the invention is to provide a pendant which is cheap, durable and neat in appearance and which can be made of any desired length and can be set at any 15 desired angle and when so set will remain firmly positioned.

The invention consists in the combination and arrangement of parts set forth in the following specification and particularly 20 pointed out in the claims.

Referring to the drawings: Figure 1 is a side elevation of an electric light pendant constructed in accordance with my invention illustrating the same as attached to the 25 ceiling. Fig. 2 is a side elevation of the same with a portion thereof shown in dotted lines in an adjusted position, both Figs. 1 and 2 being broken away to save space in the drawings. Fig. 3 is a sectional elevation 30 taken on line 3—3 of Fig. 1. Fig. 4 is a sectional plan taken on line 4—4 of Fig. 2. Fig. 5 is a plan view of one of the spring washers.

Like numerals refer to like parts throughout the several views of the drawings.

In the drawings, 5, 6, 7, 8 and 9 are links forming an adjustable support. Said links are all of them formed of hollow rectangular tubes as illustrated in Fig. 4. The terminal link 5 has a screw-threaded sleeve 10 fast to its upper end to which is fastened the supporting bracket 11. The terminal link 9 has a screw-threaded sleeve 12 fast to its lower end to which is attached the lamp socket 13. The intermediate links 6, 7 and 8 are duplicates of each other. The links 6, 7 and 8 each terminates at its opposite ends in a pair of ears 14, 14 and 15, 15. Said ears 14 lie in planes substantially at right 45 angles to the ears 15. Said ears are joined together by pivots 16 which rotatably connect the ears of adjacent links together. The ears 14 are offset at 17 (see Fig. 3) out of alignment with the ears 15 on the adjacent 50 end of the link adjacent thereto, the outer

surface of the ears 15 being flush with the outer surface of the links 6 and 7.

Each of the pivots 16 consists of a head 18 and a shank, the portion 19 of said shank adjacent to the head 18 being cylindrical, while the remainder of said shank is flattened off preferably to form a square portion 20, said square portion fitting in a corresponding hole 21 in the ear 15 to which it is riveted at 22.

The ears 15 are preferably provided with a hemispherical projection 23 in which particular portion of the ear 15 the hole 21 is provided. The ear 14 is rotatably mounted upon the cylindrical portion 19 of the pivot 70 16 and interposed between the ear 14 and the head 18 is a split spring washer 24 which presses against the inside of the head 18 on one side thereof and against the inside of the ear 14 on the opposite side thereof tending to force the ear 14 against the ear 15 to produce a frictional resistance to the rotation of the ear 14 relatively to the ear 15 and consequently presenting a frictional resistance to the rotation of one of said links 80 upon another.

The terminal link 5 is like the intermediate link 6 in so far as the ears 14 are concerned and the terminal link 9 is the same as the link 8 in so far as the ears 15 are concerned, but at the upper end of the link 5 and at the lower end of the link 9 no ears are provided. The said ends of the links 5 and 9, as hereinbefore set forth, are provided with means for attaching the supporting 90 bracket 11 and the lamp socket 13.

The electric wires leading to the lamp socket 13 extend through the interior of the tubular links forming the support and project out through the supporting bracket 11.

In use the device may be supported from a bracket fixed to the ceiling or to the wall or to any suitable stationary support. When it is desired to adjust the lamp to different positions, the links are rocked one upon the other to bring the lamp to the required position, as illustrated in Fig. 2 wherein the link 9 has been rotated upon the pivot which connects it to the link 8 and the link 7 has been rotated upon the pivot which connects it, in turn, to the link 6, and in this manner the support may be adjusted to different angles and to different positions in different planes, thus obtaining any desired position for the lamp, and when this position has 110

been obtained the lamp will stay in that position, due to the frictional resistance against relative movement of the different links as hereinbefore described.

5 I claim:

1. An adjustable support for electric lamps having, in combination, a plurality of tubular links, each link terminating at its opposite ends in a pair of ears and pivots connecting said ears together, said pivots each consisting of a head and a shank, said shank being cylindrical adjacent to said head and flat at its end, said flat end projecting through a corresponding hole in one ear of said pair of ears and being secured thereto, the other ear of said pair of ears being rotatably mounted on said cylindrical portion of said shank and a spring washer on said shank and bearing against one of said ears.
- 10 2. An adjustable support for electric lamps
- 15
- 20

having, in combination, a plurality of tubular links, each link terminating at its opposite ends in a pair of ears and pivots connecting said ears together, said pivots each consisting of a head and a shank, said shank being cylindrical adjacent to said head and flat at its end, said flat end projecting through a corresponding hole in one ear of said pair of ears and being riveted thereto, the other ear of said pair of ears being rotatably mounted on said cylindrical portion of said shank and a spring washer interposed between said head and said last named ear.

In testimony whereof I have hereunto set my hand in presence of two subscribing witnesses.

KNUT F. M. LINDBLAD.

Witnesses:

CHARLES S. GOODING,
SYDNEY E. TAFT.
